UNITED STATES PATENT OFFICE.

ARVID EK, OF PORTLAND, MAINE.

HANGER ATTACHMENT FOR GARMENTS.

1,118,750.

Specification of Letters Patent. Patented Nov. 24, 1914.

Application filed April 18, 1914. Serial No. 832,917.

To all whom it may concern:

Be it known that I, ARVID EK, a citizen of the United States, residing at Portland, in the county of Cumberland and State of Maine, have invented certain new and useful 5 Improvements in Hanger Attachments for Garments, of which the following is a specification, reference being had therein to the accompanying drawing.

10 This invention relates to improvements in garments and has particular reference to hanger attachments therefor, and which, though peculiarly useful in connection with coats is also adapted for service in similar articles of apparel, cloaks, capes, etc.

15 For a great many years it has been the universally recognized tailoring practice to fasten on the inner side of the collar portion of a coat, a short tape, cord or chain, 20 fastened to the coat immediately adjacent to the back seam or center of the back of the coat, and presenting a free or unattached intermediate part constituting a loop by which the coat may be hung on a hook or equivalent device. In the employment of 25 a hanger such as that to which I have just alluded, experience has demonstrated the fact that by reason of the weight of the garment being entirely concentrated at the

30 center of the collar or, as might be properly said, at a single point, the garment fabric and structure became stretched or distorted, resulting in an unshapely or misfitting collar,—especially true in the case of heavier 35 garments, such as cloaks and overcoats. The inner fold of the collar and adjoining back portion of the body of the garment is unduly pulled up or raised, causing an outwardly bulging or receding effect of the 40 outer fold of the collar, which, under constant hanging, became a permanent disfigurement and destroyed that nicety of fit around the neck of the user, demanded by the refined tastes of the latter.

45 The present invention has been inspired by a desire to overcome the objectionable characteristics of the ordinary hanger above discussed, and possesses as its salient feature the provision of a hanger, as a part 50 incorporated in or carried by the garment, of substantial length enabling the opposite end portions thereof to be attached to the garment above the shoulder portions thereof so that as distinguished from throwing 55 all of the supported weight of the garment at the center of the back of the collar un-

der the practice now in vogue, the supporting strains are distributed at opposite sides of the garment, or, as already intimated, at points adjacent to the shoulders where the 60 garments are usually heaviest by reason of the sleeves; or viewing the improvement from another point of view, the opposite halves of the garment may be said to be supported at widely separated or distinct 65 points.

The invention is capable of embodiment in a wide variety of forms and devices, several of which will be illustrated in the accompanying drawings, forming part hereof, to enable a clear and full understanding of the principle underlying the same and constituting a similar basis for still other 70 embodiments of the invention, not necessary to be herein illustrated, but which will 75 appeal to persons skilled in the art as coming within the scope of the invention as defined by the hereto appended claims.

Improved details in construction and arrangement of the features of a garment 80 made in keeping with the present improvements will be understood from the drawings referred to, when considered in connection with the specific description hereinafter contained.

85 In the drawings: Figure 1 is an inside view or elevation of the upper portion of a coat spread out, to better show the same, having on the inside of the collar thereof one form of my improved hanger attachment; Fig. 2 is a horizontal sectional view of the same; Fig. 3 is a view similar to Fig. 1, of another form of the attachment, and Fig. 4 is a horizontal sectional view through the same; Fig. 5 illustrates a third form of 95 hanger attachment; and Fig. 6 being a longitudinal section thereof.

Referring more specifically to the drawings A represents the upper portion of a coat, representative merely as any garment 100 in connection with which my improved hanger may be advantageously utilized; and B represents the hanger, which may be a chain, cord, tape or any other suitable material having a central exposed loop portion 105 and oppositely projecting concealed terminal portions C passed inwardly through eyelets or marginally sewed and reinforced holes D (like button-holes) from the loop portion and loosely confined between the collar 110 layers throughout the length of the terminals to their respective points of fasten-

ing, designated at E, which latter, it will be appreciated, are immediately above the shoulders of the coat. By this arrangement the supporting strains are correspondingly borne at widely separated points, namely at said shoulder portions, while at the same time an intermediate loop of substantially the conventional length, adapted to engage a hook or the like, is afforded.

10 In Fig. 3 the hanger is shown as provided with the loop B' and terminal portions C', the latter not being concealed in this instance, but loosely passing through retaining loops F of any type found expedient, for example tape or equivalent substance stitched, as at f in the seam of attachment between the collar and body of the garment. Here again the ends of the terminals are securely fastened at E at points directly above the shoulder portion of the coat.

That form of the device suggested in Fig. 5 is somewhat similar to the form of Fig. 3 in that flexible sheaves or tubes F' are stitched in the seam f' between the collar and body of the coat, and are used in lieu of the loops F. The hook engaging loop of the hanger in this instance is again represented as the middle portion thereof B², the terminals,—working loosely in the sheaves or tubes F',—at C² and the points of fastening above the shoulder portions of the garment at E².

Having thus described the invention, what is claimed is:

35 1. In a garment of the character described,

Copies of this patent may be obtained for five cents each, by addressing the "Commissioner of Patents.
Washington, D. C."

a hanger therefor having an intermediate loop portion, relatively elongated, flexible, oppositely extending terminal portions extending approximately lengthwise of the loop portion and constituting continuations thereof, the ends of the said relatively elongated portions extending to the shoulder portions of the garment and secured thereat, in combination with means for confining the terminal portions in place while permitting the central back portion of the garment to move therealong.

2. In a garment of the character described, a hanger therefor having an intermediate loop portion, and relatively elongated, flexible, oppositely extending terminal portions extending approximately lengthwise of the loop portion and constituting continuations thereof, the ends of the said relatively elongated portions extending to the shoulder portions of the garment and secured thereat, in combination with means for confining the terminal portions in place while permitting the central back portion of the garment to move therealong, said last mentioned means including inclosures concealing the terminal portions and having openings through which the intermediate loop is projected and exposed.

In testimony whereof I hereunto affix my signature in the presence of two witnesses.

ARVID EK.
